Application May 10, 1935, Serial No. 20,827

51 Claims.

(Cl. 93—6)

The present invention relates to an improved machine and method for closing filled bags, particularly paper bags adapted to contain from one pound or less up to twenty-five pounds or more of coffee, flour, sugar, or other pulverized or granular commodities. In the present machine the closing of the filled bag, which may be of single or multi-wall construction, is effected in such a manner that the open end of the bag is collapsed, folded upon itself, then folded and sealed upon the top of the package so as to form a neatly squared package. Bags are closed in the machine in such a way that no leakage can occur and the formed packages are uniformly shaped so that a plurality of filled and sealed bags may be packed in cartons or master bags with a minimum of waste space.

One object of the invention is to effect the transfer of irregularly spaced filled bags from a continuously moving supply conveyor to regularly spaced intermittently moving conveying pockets adapted to convey the bags through successive stations of an intermittently operated bag closing machine.

Another object of the present invention is to provide means to settle the contents of the filled bag and to compact the contents of the bag prior to the sealing thereof in order that uniform and sharply defined packages may be produced.

Another object of the invention is to provide means whereby fluctuations in density of the commodity being packaged may be accounted for in the formation of the sealed package. It is well known that a great number of commodities, such as coffee, flour, cocoa, and many commercial chemicals, will increase or decrease in bulk with variations in atmospheric conditions and other factors. A variation in bulk as great as five per cent may occur within the space of a few minutes, particularly since the commodity being packaged is normally dropped through the atmosphere from a storage bin into the open bag. Other factors, such as variations in the manufacturing process of the commodity and variations in the substance of the raw materials may cause a sudden change in density. A great resistance to the automatic packaging of commodities in bags has been that the finished packages were never uniform. One bag in which the commodity would be loosely and sloppily packaged would be followed by another bag in which an imperfect seal would be formed due to the commodity bulging beyond the expected bulk. A primary feature of the present invention is that any variation may be substantially instantaneously corrected.

A further object of the invention is to further the formation of attractive packages by trimming the end of the mouth of the bag at a substantially uniform distance above the top of the enclosed commodity. It has heretofore been suggested that the mouth of the bag be trimmed but this

has never been successfully accomplished since the bags were always trimmed with relation to the bottom of the bag as a datum line. With the present invention fluctuations in density of the material are accounted for by trimming the bags with reference to the top of the enclosed commodity so that the trimming of the edge of the bag mouth results in a projecting bag end of uniform length such that when the end of the bag is folded upon itself and upon the top of the package the length of bag material in each fold will be constant and the folds uniformly, tightly drawn.

These and other objects, as well as the advantages, will be apparent from a study of the following description taken in connection with the accompanying drawings, wherein like numerals refer to like parts throughout.

Referring to the drawings:

Fig. 1 is a side elevation of the entire machine, showing means for feeding filled open bags to the closing machine, and means for ejecting the closed bags from the machine;

Fig. 2 is an enlarged top plan view of the machine;

Fig. 3 is a vertical cross section, taken on line 3—3 of Fig. 1, showing means for imparting intermittent motion to the conveyor;

Fig. 4 is a vertical section taken on line 4—4 of Fig. 3;

Fig. 5 is a vertical cross section, taken on line 5—5 of Fig. 2, showing the means for transferring bags from the continuously moving feed device to the intermittently moving conveyor;

Figs. 6, 7 and 8 are detail views of a part of the transfer mechanism; Fig. 6 being taken on line 6—6 of Fig. 5; Fig. 7 corresponding to Fig. 6; and Fig. 8 being a top plan view of a portion thereof indicated at line 8—8 of Fig. 5;

Fig. 9 is a vertical section, taken on line 9—9 of Fig. 2, showing the means for tucking in the side walls of the projecting end of the bag and for collapsing the front and rear walls of the bag upon the gussets;

Fig. 10 is a vertical section, taken on line 9—9 of Fig. 2, showing a portion of the means for operating the mechanism of Fig. 9;

Fig. 11 is a horizontal sectional view, with certain parts removed, of the mechanism of Fig. 9, showing the open mouth of the bag with the gusset folding means in operation;

Fig. 12 is a horizontal cross section, taken on line 12—12 of Fig. 9, showing the means for collapsing the mouth of the bag after the gusset tucking means have operated;

Fig. 13 is a vertical cross section, taken on line 13—13 of Fig. 2, showing the means for compressing the commodity enclosed in the bag;

Fig. 14 is an enlarged view in vertical cross sec-

tion of the mechanism of Fig. 13, taken on line 14-14 of Fig. 2;

Fig. 15 is a horizontal cross section, taken on line 15-15 of Fig. 14;

5 Fig. 16 is a vertical cross section, taken on line 16-16 of Fig. 2, and illustrating the bag trimming, bag crimping and glue applying mechanism in operation;

10 Fig. 17 is a detailed view of a portion of the mechanism of Fig. 16;

Fig. 18 is a top plan view of the glue applying mechanism of Fig. 16;

15 Fig. 19 is a vertical cross section, taken on line 19-19 of Fig. 18;

20 Figs. 20, 21, 22, 23, 24 and 25 are similar views in vertical cross section taken along lines 20-20, 21-21, 22-22, 23-23, 24-24 and 25-25 of Fig. 2, respectively;

25 Fig. 26 is a vertical cross section, taken on line 26-26 of Fig. 2, showing the final folding mechanism for receiving the folded end of the bag mouth and folding it down upon the top of the package;

20 Figs. 27 and 28 illustrate the final folder in 25 succeeding positions;

Fig. 29 is a cross sectional view, taken on line 29-29 of Fig. 2, showing the mouth of the bag being held in position while the adhesive initially sets;

30 Fig. 30 is a plan view of the dyer mechanism;

Fig. 31 is a vertical cross section of the dryer mechanism;

35 Fig. 32 is an enlarged detail view of a portion of the dryer mechanism; and

Fig. 33 is a schematic plan view of the dryer cam.

Referring to Fig. 1, there is illustrated, more or less diagrammatically, a conveying mechanism comprising a horizontal belt 50 passing over 40 a table 51 between guides 52. As indicated in dotted outline there may be side belts 53 supplementing the guides and the lower belt, the belts cooperating to feed the filled bags toward the closing machine. The bags A have been previously filled and placed upon the conveying belt 50 by any suitable mechanism and are preferably jogged upon the conveying belt by any suitable mechanism. Belt 50 is driven by means of a sprocket chain 55 which in turn is driven by the 45 main shaft 56 through suitable gears. The main shaft 56 is rotated by means of a belt drive 57 (Fig. 2) from a suitable motor (not shown) and a shaft 58 and reduction gearing 59 (Fig. 1). It can be seen that the bags A are continuously 50 progressed upon the conveying belt 50 toward the closing machine, where the bags are received in an intermittent chain conveyor to be described. The conveyor 50 is preferably driven at a greater speed than the bags can be received in the machine so that they will crowd together, as illustrated in Fig. 1, the conveyor sliding beneath the temporarily stationary bags.

In Fig. 3 there is illustrated means for transforming the continuous rotation of the main shaft 56 into intermittent motion of the chain conveyor in the bag closing machine. Fixed to shaft 56 is an eccentric cam 60 which reciprocates an arm 61 pivoted at 62 to the frame 63 of the machine and having a cam follower 64 bearing against the cam. A link 65 is attached to the arm 61 and to a pawl carrier 66 loosely mounted upon a stub shaft 67 mounted in the frame of the machine. Fixed to the shaft 67 (Fig. 4) is a ratchet 68 having teeth 69, with 75 which engages the ratchet pawl 70. The stub

shaft 67 intermittently drives a vertical stub shaft 71 through gears 72, 73. The upper end of shaft 71 drives a sprocket 74 located above the top of the bed 75 of the machine. At the opposite end of the bed 75 of the machine (Fig. 2) is a corresponding sprocket 76. A continuous chain 77 is passed about sprockets 74, 76 to spaced links of which are fixed vertical plates 78 to which are bolted members 79 having forwardly extending parallel arms 80 and a rear face 81 thereby forming three-sided pockets adapted snugly to receive filled bags.

The chain conveyor is intermittently progressed to move the filled bags through a plurality of spaced stations. The first stop of a 15 conveyor pocket is in line with transfer mechanism operating to remove the foremost bag from the continuous feeding device and place it in the pocket. This is accomplished by means of the mechanism illustrated in Fig. 5.

20 Fixed to the main drive shaft 56 is a cam 90 operating a reciprocating bar 91 guided in a bearing 92 fixed to the frame 63. The bar 91 is provided with a guide opening through which the main shaft passes and with a cam follower 25 93 bearing against the cam. The forward extremity of the bar is provided with a vertical yoke member 94 in which is received a roller 95 mounted upon a rocking lever 96 pivoted to the frame. A cord 97 is attached to the upper end 30 of the rocking lever 96 and extends around a pulley 98 to a weight 99 which keeps the cam follower 93 bearing against cam 90. Each revolution of the main shaft 56 will cause the rocking lever 96 rapidly to swing inward toward the 35 frame, to remain there while the cam follower is in engagement with the high portion of cam 90, rapidly to return, and to remain in returned position throughout substantially 180° rotation 40 of the shaft.

The bags are forced by the succeeding bags from the conveyor 50 onto an intermediate table 100. In order that they may be transferred to a bottom guide rail 101 associated with the table top 75, there is provided transfer mechanisms as 45 follows: A guide rod 102 is fixed to the bottom of table 100 and guides a slide 103, to the bottom of which is pivoted a hooked arm 104 having a latching extension 105. The arm normally rests in the position illustrated in full line in Fig. 5 so 50 as to engage with a hook 106 at the upper end of rocking lever 96. A tension spring 107 is extended from the slide 103 to a fixed extension 108. Upon inward movement of the rocking lever, the slide 103 will be caused to move toward the conveyor pocket positioned to receive the bag. Upon retraction of the rocking lever, the spring 107 will retract the slide. A pusher plate 110 is fixed to the slide 103, the plate being formed so as to provide a pushing surface at its forward extremity and a temporary restraining surface at one side to prevent a succeeding bag from becoming fouled. The slide is prevented from retracting too far by means of a plate 111 which supports the extension 108, plate 111 being attached 60 to the outer end of the guide 102.

If the supply of bags to the intermediate table 100 is uninterrupted each reciprocation of slide 103 will transfer a bag into each of the pockets on the conveyor. However, the supply of bags 70 may be momentarily interrupted so that a bag would be but partially beyond the limits of the guides 52 when the slide 103 started to reciprocate, with the result that a bag would be sheared into two sections or the mechanism would be 75

considerably damaged. In order to prevent this there is provided a safety device which will prevent reciprocation of slide 103 until a filled bag is exactly in registry with the conveyor pocket. 5 Pivoted at 115 to the intermediate table 100 is a stop plate 116. A spring 117, attached to a rod extending from plate 116, tends to pivot the plate about 115 and toward the oncoming bags. A rod 118, also fixed to plate 116, limits the pivotal movement thereof by engagement with spaced pins 119, 120 mounted on table 100. The spring 117 tends to keep rod 118 against pin 119 but the force of the oncoming bags will rotate rod 118 against pin 120. In Fig. 2 a bag has rotated the plate and has thereby partially rotated an arm 121 fixed to the pivot 115. The forward extremity of arm 121 carries a latch 122, which is biased by a spring 123. If, as seen in Fig. 6, a bag has pivoted the arm 121, the latch 122 will be maintained out of the path of the latching extension 105. If, however, a bag has not fully reached the proper position, the latch 122 will engage extension 105, as seen in Fig. 7. The spring 123 prevents undue shock of such engagement. The slide 103 travels a slight distance onward until it is stopped by plate 111, the result being to lift the hooked arm 104 into the position shown in dashes in Fig. 5. Any number of reciprocations of rocking lever 96 can occur 30 without reciprocating the slide 103 until a bag rocks arm 121 as in Fig. 6, whereupon hooked arm 104 will drop and engage with the hook 106. The extremities of arm 104 and lever 96 are bevelled so that the lever 96 may return beneath 35 the arm 104 even though it drops during the time that the lever is in forward position. As seen in dot and dash lines in Fig. 5, the pusher plate 110 is moved forward far enough to clear an outer guide rail 125 which extends along the front of 40 the closing machine.

The filled bag, now positioned in the conveyor pocket, is progressed along the surface of the bottom guide 101. In order to maintain the pockets in correct alignment there is provided a 45 longitudinal tongue and groove 130 at each side of the bed 75, engaging with tongues and a groove on the lower surface of the conveyor pocket supports (Fig. 9). The guide 125, retaining the bags in the pockets, is supported on a plurality of up- 50 right bars 131 mounted on the bottom guide 101, the means of attachment of the guide rail 125 thereto comprising a plurality of thumb screws 132 by means of which the rail may be adjusted. The filled bag is progressed into the mechanism 55 of Fig. 9 by the first movement of the conveyor and comes to rest with its open mouth projecting into the path of means operating to tuck the side walls inwardly to form a gusseted mouth and to collapse the front and rear walls inwardly upon 60 the gussets.

Fixed to the main shaft 56 is a cam 135 (Figs. 1 and 10) which, through a yoked guide 136 and cam follower 137, operates an adjustable pitman 138. A lever 139 pivoted to the pitman 138 is 65 fixed to a rock shaft 140 extending parallel to the main shaft to a point beneath the mechanism of Fig. 9. A lever 141 fixed to the end of rock shaft 140 operates a pitman 142 (Figs. 1, 9 and 10) which operates the gusset tucking means. The 70 frame 63 is provided with an auxiliary frame 145, which carries a guide plate 146. A block 147 is guided by the edges of a longitudinal slot in plate 146 and a second block 148 is guided by the outer edges of plate 146. Block 147 is reciprocated by 75 means of a lever 150 attached to pitman 142, a

rock shaft 151, and a lever 152 projecting into a slot in the block. The upper surface of block 147 carries a wedge 155 and an adjustably mounted bag presser 156. A tension spring 157 is attached to wedge 155 and to a flange at the rear of block 148, the tension of the spring being adjustable by means of a suitable tensioning device 158. Forward motion of block 147 will therefore cause block 148 to follow in abutting relation. At the side of guide plate 146 is an adjustable abutment 10 160 which engages block 148 and prevents forward movement thereof even though block 147 continues to travel and spring 157 is placed upon considerable tension. Block 148 carries pivots 161 and 162 upon which are mounted brackets 15 163, 164, respectively. Each bracket is provided with a plurality of pairs of lugs, to the rear pair of which, 165, is pivoted a tucking bar 166 which passes between the forward pair of lugs 161. The tucking bars are constrained to pivot with 20 brackets 163 and 164 about the pivots 161 and 162, but may swing upward about lugs 165 if necessary. The tucking bars will normally remain in the position illustrated, but, should the bag be filled to a greater extent than normal, 25 the tucking bars may rise while still performing their function, or they may be pivoted out of operative position if desired.

Each bracket carries a roller 170 which engages the adjacent side of the wedge 155. When 30 blocks 147 and 148 are in contact the tucking bars 166 will be maintained at an angle to each other in the position indicated in skeleton outline in Fig. 11. Each tucking bar is provided at its forward end with a tucking member 171 which 35 is moved forward with the block 148 to the side of the bag. The abutment 160 is adjusted so that the points of the tucking members will stop adjacent the center line of the bag regardless of the 40 width of the bag and regardless of the amount of further travel of block 147. When brought to a stop the tucking members are held apart, but continued movement of block 147 will cause the tucking members to approach each other due to 45 the urge of a tension spring 172 joining the tucking bars 166, and due to the rollers 170 following the converging surface of the wedge 155. The amount of continued movement of wedge 155 is determined by the adjustment of pitman 138 (Fig. 10) thereby providing for varying depths of 50 bag gussets. It is seen that the bag presser plate 156 is provided with a depending flange 175 which engages the side of the bag when the block 147 is at its foremost position. The presser plate is provided with a slot 176 by means of 55 which it may be adjusted to accommodate different sizes of bags.

The operation of the foregoing mechanism is as follows: As the bag comes to a rest, the tucking members 171 are brought forward to opposite 60 sides of the bag. Continued movement of wedge 155 causes the flange 175 of the presser member to engage the front of the bag and to square the bag top in the conveyor pocket, and also causes 65 the convergence of tucking members 171 to draw the sides of the bag in between the front and rear faces. The shape of cam 135 (Fig. 10) causes the mechanism to remain in the position of Fig. 11 momentarily, then rapidly to withdraw to its starting position, thereby withdrawing the presser member, opening the tucking members and reTRACTING the entire mechanism to the position of Fig. 9, thereby allowing the bag to move on and the succeeding bag to be brought into position. 70 Before the retraction is permitted, however, other 75

mechanism operates upon the mouth of the bag to collapse the front and rear faces against the tucked gussets.

The collapsing mechanism comprises a cam 180, fixed to main shaft 56, operating an adjustable vertical pitman 181 by means of a guide yoke 182 and a cam follower 183, a tension spring 184 fixed to the bed 75 and to yoke 182 maintaining the cam follower against the cam. The pitman 181 extends upward alongside a standard 185 provided with an extension 186 overlying the bag, and is attached to a lever 187 pivoted to the standard at 188. An upright 190 fixed to the extension 186 is provided with a vertical slot 191 in which is guided a pin 192 passing through a horizontal slot 193 in lever 187. Spaced depending arms 194 attached to extension 186 pivotally support spaced bag engaging shoes 195. Short levers 196 fixed to the shoes 195 are pivoted to links 187 which are pivoted to the pin 192. Raising of pitman 181 causes pin 192 to be lowered, thereby rocking the shoes 195 about their pivots to engage the front and rear faces of the bags and draw them together. The shoes are convex in form so as to wipe the faces of the bag upwardly, thereby smoothing and correctly collapsing the same against the tucked side walls. The operation performed by this mechanism is so timed that the shoes commence engaging the bag walls at substantially the instant that the tucks are formed therein, and progressively wipe upward and squeeze the front and rear walls together during the short dwell that the tucking members are permitted at their operating position. The action is practically instantaneous due to the shape of cam 180. Immediately upon reaching their full engaging stroke the cam 180 commences to withdraw the shoes, this however being accomplished very slowly due to the shape of the cam. It will therefore be apparent that the shoes will form guideways between which the collapsed mouth of the bag will be held in substantially collapsed position until the bag is moved forward to the next station. During the forward movement into the next station the mouth of the bag is guided between spaced guide members 200 which prevent unfolding of the collapsed bag mouth.

The bag is brought to rest at the next station 50 of the machine, comprising means for securing the upper end of the bag and to compress the commodity into the bag so that a substantially flat-ended package may be formed. This mechanism is illustrated in Figs. 13, 14 and 15. A cam 205 fixed to the main shaft 56 operates a vertical pitman 206 through a guide yoke 207 and a cam follower 208 maintained against the cam by a spring 209 fixed to the bed 75. Pitman 206 passes through an adjustment block 210 which 60 carries an extension rod 211 extending above a standard 212 mounted on the bed. Spaced extensions 213, fixed to standard 212, extend over the bag and adjustably support guide plates 214. The front face of standard 212 is provided with flanges 215 which guide a vertically reciprocable arm 216 extending over the bag in the space between the arms 213. The lower face of arm 216 is provided with a notch in which fits a rounded abutment 217 fixed to the extension 211 of pitman 206. A similar rounded member 218 is loosely guided by rod 211 and is pressed against the top of arm 216 by a compression spring 219. Reciprocation of pitman 206 will cause vertical reciprocation of arm 216 unless prevented by 75 some obstruction, whereupon the spring 219 will

allow the pitman to reciprocate without movement of arm 216. Arm 216 carries a spaced pair of rear rods 220 and a spaced pair of forward rods 221 which pass between the arms 213 and are guided by guide pins 222 and 223, respectively, which pass through guide slots 224 and 225, respectively, in the side plates 214. The upper extremities of the guide slots are divergent so that the rods 220, 221 are spread apart when arm 216 is raised. Upon downward movement of the arms the rods are brought together then moved downward in substantially parallel relation until retracted. Retraction is first in parallel lines and then divergent. A bar 230 extends between arms 213 and a strip 231 of textile material, such as heavy canvas, is draped over the bar at substantially its middle point. The ends of the canvas strip extend downwardly beyond the ends of the rods 220, 221. The lower ends of each pair of rods are provided with a flat vertical clamping plate 232, which is bent horizontally to provide a pressing surface 233 and terminates in a rounded outer end. The ends of the canvas strip are brought around the pressing surfaces and are attached to tension springs 234 and 235 which are fixed to the arm 216.

The plates 214 are provided with throat portions 240 into which the guides 200 lead the collapsed mouth of the bag during the time that the arm 216 is raised as shown in full line in Fig. 13. At this time the rods 220, 221 are spread apart, thereby spreading the sections of the canvas strips beyond the limits of the throat 240. Immediately upon the bag coming to rest arm 216 commences to lower, the plates at the ends of the rods 220, 221 sliding upon the outer surface of the canvas. The slots in plates 214 will cause the bag mouth to be clamped and held in the same relative position due to the lack of movement of the canvas strip. Continued movement of the arm 216 causes the pressing faces 233 to squeeze down upon the contents of the bag while continually drawing together the sides of the bag end. If the height of the filled bag is greater than normal, pitman 206 may continue in its downward travel, 45 spring 219 however permitting arm 216 to remain stationary.

The next station of the machine comprises means to trim the edge of the bag mouth, to crease the bag mouth a uniform distance below the 50 trimmed end, and to apply adhesive to the bag mouth at the parts which are to be folded and sealed. The trimming and creasing mechanism is illustrated in Figs. 16 and 17.

A cam 245 fixed to the main shaft 56 operates a pitman 246 through a guide yoke 247 and a cam follower 248. Pitman 246 extends upward through the bed 75 and is pivoted to a bell crank lever 249 which is pivoted to a bracket extension 250 extending over the top of the bag. The 60 bracket extension is provided with a throat portion 251 which receives the top of the bag and which is provided with a fixed shear blade 252 and a fixed crimping blade 253. Plungers 254 are guided in the opposite side of the bracket extension and carry a movable spring-pressed shear blade 255 and movable crimping jaws 256. The plungers carry a plate 257, between which and the extension 250 are mounted springs 258. The forward arm of bell crank 249 is provided with a 70 rounded surface which bears against plate 257. Upward movement of pitman 246 causes the shear blades to trim the mouth of the bag and the crimping mechanism to place a horizontal crease parallel to the trimmed edge at a uniform dis- 75

tance therefrom in the bag material. The 5 spring 258 serves to maintain cam follower 248 against cam 245. The operative portion of cam 245 is extensive and maintains the plunger in operative position throughout a substantial period, during which time adhesive is applied to the front face of the bag in the area between the crease and the front vertical face of the bag.

The adhesive applying mechanism is illustrated in Figs. 16, 18 and 19. The mechanism is supported on a bracket 260 fixed to the frame of the machine. A motor 261 (Fig. 1) is supported by the bracket and drives reducing gears 262 through a sprocket chain 263. A sprocket chain 264 drives a shaft 265 supported in bearings on the bracket and which carries a fountain roll 266 mounted in a container 267 carrying the adhesive. The container 267 is supported in an outer container 270 in which water is placed and heated by suitable heating elements 271. With certain types of adhesive the heating elements are unnecessary but the preferable adhesive is of the type which is maintained in liquid condition by heat and which sets upon cooling. The fountain roll 266 continuously revolves in the adhesive and its surface is cleaned by an adjustable doctor blade 272.

In Figs. 16, 18 and 19 there is illustrated means for transferring the adhesive to the surface of the bag. The transfer mechanism is operated by a cam 275 fixed to the main shaft 56. The cam operates an adjustable pitman 276, through a yoke guide 277 and a cam follower 278, which rocks a bell crank 279 pivoted to the extension of the frame. Bell crank 279 is fixed to a rock shaft 280 which extends beneath the transfer roll to its opposite side and to which is attached a lever 281. The free ends of bell crank 279 and lever 281 are pivoted to transfer roll supporting arms 282 which have the shaft of the transfer roll 283 rotatably mounted thereon. A spring 284 is stretched between bell crank 279 and arm 282 to maintain a guide roller 285 against a cam plate 286. A spring 287 maintains a guide roller 288 against a cam plate 289 at the opposite side of the mechanism. Reciprocation of the pitman 276 moves the transfer roll from the position shown in skeleton outline (Fig. 16) to its operative position shown in full line. The shaft of the fountain roll carries a gear 290 which meshes with a gear 291 upon the shaft of the transfer roll to rotate the transfer roll during the time that it is positioned against the surface of the fountain roll thereby causing a layer of adhesive to be deposited upon its surface. A rack 295 is fixed to the side of the adhesive container in position to engage the gear 291 as it is lifted from engagement with the gear 290 and moved toward the bag. The purpose of the rack is to cause the transfer roll continuously to revolve in order that the adhesive will not collect at any one point upon its surface. The transfer roll spreads adhesive first upon the shoulder of the bag and may then be lifted to roll upward along the portion of the bag between the crease and the shoulder. It is preferably knurled, as illustrated, thereby accumulating a greater amount of adhesive to transfer to the bag. Upon retraction of the pitman the transfer roll rolls back along the surface of the bag and the gear 291 is caused to engage first with the rack 295 and then with the gear 290. The adhesive applying mechanism is preferably enclosed in a housing 296 having a trap door 297 (Fig. 2). The housing serves the dual function 75 of retaining the heat in an enclosed area and also

prevents the trimmings from the bags from dropping into the adhesive applicator. Immediately after disengagement of the transfer roll from the bag the shear blades and the crimping jaws are opened and the bag is progressed to the next 5 station.

The action of the crimping jaws and shear blade of the preceding mechanism tends temporarily to unite the plies of the bag mouth. Immediately upon leaving the crimping mechanism the mouth 10 of the bag enters a stationary converging guideway comprising an upper forming rail 300 and a lower forming rail 301 mounted upon a bracket 302 fixed to the bed 75 (Figs. 20, 21 and 22). The passageway between the guide rails is twisted 15 through 90° so that the bag mouth is folded along the provided crease as shown in Fig. 22. Immediately upon leaving the first set of guide rails the bag mouth enters a second set comprising an upper forming plate 305 and a lower forming plate 306 mounted upon a bracket 307 fixed to the bed 75. At the entrance to this second set of guide rails the upper plate 305 is substantially horizontal and the lower plate 306 is curved away from the vertical axis of the bag. At the middle 20 of this set of guide rails (Fig. 24) each plate has approached a vertical position and at the exit therefrom (Fig. 25) the plates are parallel and vertical and the bag has been given a first fold 25 upon itself along the fold line provided by the 30 creasing jaws.

The folded bag now comes to rest in the final folding mechanism illustrated in Figs. 26, 27 and 28. This mechanism comprises a cam 310 fixed to the main shaft 56 operating an adjustable 35 pitman 311 through a yoked guide 312 and a cam follower 313. The pitman rocks a lever 315 fixed to a rock shaft 316 mounted upon the bed. A bracket 317 supports the final folding mechanism which is operated by a lever 318 rocked by a shaft 316. A sliding frame 320 is guided in suitable guides 321 mounted upon the bracket 317, and is substantially restrained from upward movement by a plurality of adjustable springs 322 and 323. The forward end of the frame carries spaced 40 cam plates 324 and a pivoted rod 325. Mounted upon the rod are cam levers 326 in the free arm of which is mounted a pivot pin 327. Fixed to the pivot pin 327 is a folding clamp 328 and an operating lever 329. A clamping plate 330 is 45 fixed to the cam levers 326. A link 335 extends from the free end of operating lever 329 to the free end of the lever 318. A pin 336 fixed to an extension of the cam levers 326 is a support for one end of a spring 337 extending to a pin 328 50 carried by the sliding frame 320.

The operation of the final folding mechanism is as follows: The mechanism is in the position illustrated in Fig. 26 as the bag comes to rest after leaving the preliminary folding means. The 60 forward motion of the rod 335 causes the clamping plate 328 to grip the folded end of the bag against the clamping plate 330 and causes the pivot pin 327 to describe an arc about the folding clamp 328, thereby moving the folded end 65 through a 90° arc to the position shown in Fig. 27 and drawing the sides of the bag taut. Further movement of lever 318 will now cause forward movement of the sliding frame 320 thereby causing the clamping plate and folding clamp to 70 tighten the fold, draw the bag taut, and slidably to release the folded end of the bag. A pressing plate 340 is provided upon the end surface of the frame which engages the folded end and presses it downwardly upon the upper end of the 75

bag as illustrated in Fig. 28. In Fig. 28 the body of the bag is shown as lower than would ordinarily be the case, merely to clarify the operation of the device and to show the normal line of adhesive at B. In operation the machine is adjusted so that the pressing plate 340 will press the folded end of the bag firmly upon the adhesive, and the folded end will be pressed firmly against the shoulder of the bag, the compression imparted to springs 322, 323 determining the amount of pressure. The springs also permit operation of the device if a bag is filled too full. Retraction of pitman 311 causes the clamping lever 328 to separate from the clamping plate 330 and return 15 of the entire device to its original position.

It has been found to be helpful although not entirely necessary to the operation of the folding mechanism and the folding guides to extend a nearly rigid rod 341 parallel to the guide rail 10 20 125 in position to engage the rear shoulder of the bag as it passes through the folding stations.

Immediately upon retraction of the final folding device the bag progresses beneath a stationary pressing plate 345 (Figs. 1, 2 and 29). The 25 plate 345 comprises a curved plate which extends partially around the end of the bed 75 and is supported on uprights mounted in a bracket 346 supported by the frame. The feeding movement of the chain conveyor is such as to remove the 30 bag from the final folding mechanism to a position upon the longitudinal center line of the machine, from which the bag will be ejected as will presently appear.

It will be apparent that each of the foregoing 35 mechanisms operates in such a manner that ordinary fluctuations in density and quantity will be compensated. It has been found, however, that as small a package as one pound of coffee will vary as much as three-quarters of an inch more 40 or less in height within as short a time as one-half hour. In as short a space as five minutes the bulk of the coffee may vary so much as to cause a loose package to result. In order that instantaneous adjustment of the entire machine may be 45 brought about there has been provided means to adjust the level of the bottom guide rail 101 whereby uniform packages can be formed. The means comprises vertically reciprocating supporting posts 380, 381 upon which the guide rail 101 50 is mounted. The lower end of each post is formed with rack teeth meshing with a pinion mounted upon a shaft 352 rotated by a worm gear 353 and a worm 354 and hand wheel 355 (Fig. 16). The operator of the machine can instantaneously 55 raise or lower the guide rail 101 thereby altering the position of the top of the enclosed contents of the bag with respect to the operating mechanism. Since the normal operating capacity of the machine is from thirty to forty bags per minute the effect of any adjustment will be very rapidly observed.

The closed and sealed bags are ejected from 60 the machine and maintained in closed position for a substantial period of time until the adhesive has set sufficiently to prevent unfolding of the 65 rolled bag end. The ejecting and drying mechanism is illustrated in Figs. 1 and 2. A vertical rock shaft 360 is provided with an arm and cam follower 361, the cam follower being held against a cam 362, fixed to the main shaft 56, by suitable spring means (not shown). At its upper extremity the shaft 360 is provided with a pair of ejecting arms 363 and 364, arm 363 engaging the upper end of the bag between the presser plate 70 75 345 and the top of the conveyor pockets and arm

364 engaging the bottom of the bag between the bottom of the conveyor pockets and the top of the guide rail 101. The cam 362 rocks the ejecting arms outward immediately upon the bag coming to rest and the spring returns the arm to normal position before the next bag approaches. The ends of the ejecting arms are bevelled as seen in Fig. 2 to provide clearance for the on-coming bag.

The bags are ejected from the closing machine into a drying mechanism more or less diagrammatically illustrated in Fig. 1 and fully detailed in Figs. 30-33, inclusive. The drying mechanism comprises an endless revolving shelf or rack 370 continuously rotated by means of a 15 sprocket chain 371 driven by the main shaft 56 and an intermediate shaft 372 supported in bearings in a stationary frame 373. A bracket 374 mounted on frame 373 carries a pivoted trans- 20 verse shelf 375 extending to the bottom guide rail 101 and providing a support for the transferred bags which will swing adjustments of the bottom guide rail or the dryer mechanism. The top of the bag is maintained in closed position by means of an intermediate presser plate 376 25 pivoted to presser plate 345 and having an arm engaged by a spring 378 to maintain suitable pressure against the top of the bag.

The dryer shelf is associated with a plurality of vertically sliding plungers 380 having rollers 381 which engage a continuous track carried by the frame 373. A pressing shoe 382 is fixed to each plunger 380 and the track is provided with a cam portion 383 which raises and lowers the 30 shoes onto the tops of the bags.

Each plunger is provided with a cross rod 390 to which are fixed tension springs 391 and 392 whose opposite ends are fixed to the back of the drying shelf. As the rollers 381 engage the cam 383 the shoes are gradually raised above 40 the level of the tops of the bags and are maintained in raised position until the bag is received from the closing machine, whereupon the shoes are gradually lowered until the roller 381 leaves the cam track. The shape of the cam 383 de- 45 termines the extent to which the shoes are raised and the strength of the springs 391 and 392 determines the extent to which the shoes are lowered. If the bags are of thin material it may be best to provide the plungers 380 with abut- 50 ments 393 which engage the back of the drying shelf and prevent further downward movement of the shoe after it has engaged the top of the bag. However, if the abutments 393 are omitted the cam track prevents the plungers from con- 55 tinued downward movement.

The driving shelf 370 is supported by spokes 400 radiating from a hub 401 which is rotated by a worm and gear driven by the intermediate 60 shaft 372 and supported by an upright post 402. A collar 403 fixed to the post is provided with a bearing raceway and a suitable bearing prevents undue friction between the hub 401 and the collar. The cam track 383 is carried by the 65 collar 403. The post 402 is supported in a standard 404 through which the post is threaded, providing means whereby the level of the drying shelf may be adjusted. A lock nut 405 is pref- erably provided to prevent the post from acci- 70 dentally turning.

The drying shelf is continuously rotated and the ejecting mechanism in the bag closing machine is so timed with respect to the drying mechanism that a bag will be positioned beneath each of the shoes 382 as it travels past the end 75

of the closing machine. Each shoe is thereupon lowered onto the top of the bag and will be maintained in lowered position by the springs 391, 392 until the shoe is raised by cam 383. At the point where the shoes are raised there is provided means to remove the bags from the drying shelf, comprising a curved guide rail 410 which extends toward the back of the drying shelf and is curved outwardly therefrom to eject the bags from the shelf. A table 411 is associated with the rail 410 and the bags are collected upon the table and removed by the operator to be packaged in master bags or cartons.

A brief résumé of the operation of the machine is as follows: Previously filled open mouth bags are converted by a continuous feeding and jogging conveyor and transmitted to an intermittent pocketed conveyor which carries the bags through the closing mechanism. At the first stop the side walls of the bag mouth are tucked inwardly and the front and rear walls collapsed upon the tucked-in side walls. At the next stop the mouth of the bag is pressed together while the contents of the bag are compressed by the gripping and compressing mechanism. At the next stop the edge of the bag is trimmed, a folding crease is provided parallel to the edge of the bag and at a uniform distance therefrom, and a quantity of sealing adhesive is applied to the shoulder of the bag upon which the folded mouth is to be sealed. The next two successive forward movements and stops will occur while the bag is passing through the preliminary folding mechanism of Figs. 20, 21 and 22, and the secondary folding mechanism of Figs. 23, 24 and 25, the bag mouth being first folded 90° along the folding crease and then an additional 90° along the folding crease. At the next stop the folded end of the bag is engaged, drawn tightly toward the front of the bag and pressed down onto the adhesive. During the next forward movement the sealed end is retained in sealed position, and at the next stop the bag is ejected into the intermediate guideways between the sealing mechanism and the drying mechanism. As two or three bags are ejected from the machine the foremost will be clamped between the rotating shelf and the pressing shoe in the dryer. After being held in the dryer for a suitable length of time the filled and sealed bag is removed and packed.

There has been illustrated and described a preferred embodiment of the invention as actually placed in operation. However, it will be appreciated that numerous alterations in arrangement and detail will be apparent to those skilled in the art and I do not intend to be limited to the exact form described except in so far as determined by the following claims which are to be construed in their broadest sense.

I claim:

1. A machine for closing the mouths of filled bags comprising, means to tuck the side walls of the open end of the bag inwardly and to collapse the front and rear walls of the bag upon the tucked side walls, means to form squared shoulders on the bag, and means to fold the end of the bag down upon one of said squared shoulders comprising a trimming device adapted to trim the edge of the bag at a certain distance above the enclosed contents.

2. A machine for closing the mouths of filled bags comprising, means to tuck the side walls of the open end of the bag inwardly and to collapse the front and rear walls of the bag upon

the tucked side walls, means to form squared shoulders on the bag, and means to fold the end of the bag down upon one of said squared shoulders comprising a combined trimming and creasing device adapted to trim the edge of the bag at a certain distance above the enclosed contents and to form a crease in the bag parallel to and at a uniform distance from the trimmed end. 5

3. A machine for closing the mouths of filled bags comprising, means to tuck the side walls of the open end of the bag inwardly and to collapse the front and rear walls of the bag upon the tucked side walls, means to form squared shoulders on the bag, means to fold the end of the bag down upon one of said squared shoulders comprising a combined trimming and creasing device adapted to trim the edge of the bag at a certain distance above the enclosed contents and to form a crease in the bag parallel to and at a uniform distance from the trimmed end, and folding bars adapted to fold the end of the bag once upon itself along said creased line. 10

4. A machine for closing the mouths of filled bags comprising, means to tuck the side walls of the open end of the bag inwardly and to collapse the front and rear walls of the bag upon the tucked side walls, means to form squared shoulders on the bag, means to fold the end of the bag down upon one of said squared shoulders comprising a combined trimming and creasing device adapted to trim the edge of the bag at a certain distance above the enclosed contents and to form a crease in the bag parallel to and at a uniform distance from the trimmed end, folding bars adapted to fold the end of the bag once upon itself along said creased line, and means to fold the folded end of the bag down upon the said shoulder. 20

5. A machine for closing the mouths of filled bags comprising, means to tuck the side walls of the open end of the bag inwardly and to collapse the front and rear walls of the bag upon the tucked side walls, means to form squared shoulders on the bag, means to fold the end of the bag down upon one of said squared shoulders comprising a combined trimming and creasing device adapted to trim the edge of the bag at a certain distance above the enclosed contents and to form a crease in the bag parallel to and at a uniform distance from the trimmed end, means to apply adhesive to said shoulder, folding bars adapted to fold the end of the bag once upon itself along said creased line, and means to fold the folded end of the bag down upon the said shoulder. 40

6. A machine for closing the mouths of filled bags comprising, means to tuck the side walls of the open end of the bag inwardly and to collapse the front and rear walls of the bag upon the tucked side walls, means to form squared shoulders on the bag, means operating to fold the end of the bag down upon one of said squared shoulders comprising a combined trimming and creasing device adapted to trim and crease the bag at a certain distance above the enclosed contents, and intermittently actuated conveyor pockets to progress the bag through said means. 60

7. A machine for closing the mouths of filled bags comprising, means to tuck the side walls of the open end of the bag inwardly and to collapse the front and rear walls of the bag upon the tucked side walls, means to form squared shoulders on the bag, means operating to fold the end of the bag down upon one of said squared shoul- 70

75

- prising a trimming device adapted to trim the edge of the bag at a certain distance above the enclosed contents; and intermittently actuated conveyor pockets to progress the bag through said means; in combination with a continuous conveying device to deliver filled bags to said machine, and a continuously rotated shelf having pressing shoes associated therewith adapted to receive and hold the closed bags as they are ejected from the closing machine.
17. A machine for closing the mouths of filled bags comprising; means to tuck the side walls of the open end of the bag inwardly and to collapse the front and rear walls of the bag upon the tucked side walls; means to form squared shoulders on the bag; means to fold the end of the bag down upon one of said squared shoulders comprising a combined trimming and creasing device adapted to trim the edge of the bag at a certain distance above the enclosed contents and to form a crease in the bag parallel to and at a uniform distance from the trimmed end; and intermittently actuated conveyor pockets to progress the bag through said means; in combination with a continuous conveying device to deliver filled bags to said machine, and a continuously rotated shelf having pressing shoes associated therewith adapted to receive and hold the closed bags as they are ejected from the closing machine.
18. A machine for closing the mouths of filled bags comprising; means to tuck the side walls of the open end of the bag inwardly and to collapse the front and rear walls of the bag upon the tucked side walls; means to form squared shoulders on the bag; means to fold the end of the bag down upon one of said squared shoulders comprising a combined trimming and creasing device adapted to trim the edge of the bag at a certain distance above the enclosed contents and to form a crease in the bag parallel to and at a uniform distance from the trimmed end; folding bars adapted to fold the end of the bag once upon itself along said creased line followed by means to fold the folded end of the bag down upon the said shoulder; and intermittently actuated conveyor pockets to progress the bag through said means; in combination with a continuous conveying device to deliver filled bags to said pockets, and a continuously rotated shelf having pressing shoes associated therewith adapted to receive and hold the closed bags as they are ejected from the closing machine.
19. In a filled bag closing machine, means to crease the mouth of the bag along a line parallel to its edge and means simultaneously to trim the edge of the bag at a uniform distance from said crease, said creasing device comprising means to grasp the mouth of the bag to hold the same against pressure on the side of the bag, and means to apply adhesive to the side of the bag below the said crease while so held.
20. In a filled bag closing machine, means to crease the mouth of the bag along a line parallel to its edge and simultaneously to trim the edge of the bag at a uniform distance from said crease, said creasing device comprising means to grasp the mouth of the bag to hold the same against pressure on the side of the bag, and means to apply adhesive to the side of the bag below the said crease while so held; said applying means comprising a fountain roll and a transfer roll reciprocated from said fountain roll to the bag.
21. In a filled bag closing machine, means to crease the mouth of the bag along a line parallel to its edge and simultaneously to trim the edge of the bag at a uniform distance from said crease, said creasing device comprising means to grasp the mouth of the bag to hold the same against pressure on the side of the bag, and means to apply adhesive to the side of the bag below the said crease while so held, said applying means comprising a fountain roll and a transfer roll reciprocated from said fountain roll to the bag, and means associated therewith to revolve said fountain roll during the reciprocation thereof.
22. In a filled bag closing machine, means to compress the material within the bag and to form squared shoulders upon said bag, comprising a strip of fabric tensioned over a stationary member above the bag and having its ends projecting downwardly at opposite sides of the mouth of the bag, and means to bring the ends of said fabric strip together to grip the mouth of the bag.
23. In a filled bag closing machine, means to compress the material within the bag and to form squared shoulders upon said bag, comprising a strip of fabric tensioned over a stationary member above the bag and having its ends projecting downwardly at opposite sides of the mouth of the bag, and means to bring the ends of said fabric strip together, said means comprising vertical gripping plates terminating in horizontal pressing plates adapted to slide upon the outer surface of said fabric strip.
24. In a filled bag closing machine, a device for compressing the material within the bag and for forming squared shoulders upon the bag, comprising rigid members to hold the upper portion of the mouth of the bag, and flexible means associated therewith to grip the entire bag mouth progressively downward from said upper portion toward the top of the contents of the bag whereby the sides of the bag are tautly drawn into substantially right-angular configuration defined by the upwardly extending mouth and the portions of the bag above the contents.
25. In a filled bag closing machine, a device for compressing the material within the bag and for forming squared shoulders upon the bag, comprising rigid members to hold the upper portion of the mouth of the bag, and flexible means associated therewith to grip the entire bag mouth progressively downward from said upper portion toward the top of the contents of the bag whereby the sides of the bag are tautly drawn into substantially right-angular configuration defined by the upwardly extending mouth and the portions of the bag above the contents, said rigid members comprising portions adapted to press upon the top of the contents of the bag at each side of the mouth.
26. In a filled bag closing machine, a device for compressing the material within the bag and for forming squared shoulders upon the bag, comprising rigid members to hold the upper portion of the mouth of the bag, flexible means associated therewith to grip the entire bag mouth progressively downward from said upper portion toward the top of the contents of the bag whereby the sides of the bag are tautly drawn into substantially right-angular configuration defined by the upwardly extending mouth and the portions of the bag above the contents, said rigid members comprising portions adapted to press upon the top of the contents of the bag at each side of the mouth, and means associated therewith to limit the pressure applied to the bag contents.
27. In a filled bag closing machine, means to

- collapse and fold the open projecting end of a bag upon itself, and means to grasp the folded end and to fold the same upon the end of the bag, said grasping and folding means comprising a clamping plate and a clamping jaw movable across the top of the bag in the direction of folding and adapted slidably to draw the sides of the bag taut and to yieldably press said folded end upon the end of the bag.
- 5 28. In a filled bag closing machine, means to collapse the open projecting end of a bag, means to apply adhesive to one wall of the bag, means to fold the mouth of the bag upon itself, and a final folding means to fold the folded end upon the area having adhesive thereon, said final folding means operating in the direction of the fold to draw the sides of the bag taut and to press the folded end upon the area having adhesive thereon.
- 10 29. A machine for closing the mouths of filled bags comprising, means to tuck the side walls of the open end of the bag inwardly and to collapse the front and rear walls of the bag upon the tucked side walls, means to form squared shoulders on the bag, means to fold the end of the bag down upon one of said squared shoulders comprising a combined trimming and creasing device adapted to trim the edge of the bag at a certain distance above the enclosed contents, all 15 of said means being relatively fixed, and means to adjust the bags toward and away from said means whereby to compensate for fluctuations in density of the enclosed material.
- 20 30. A machine for closing the mouths of filled bags comprising, means to tuck the side walls of the open end of the bag inwardly and to collapse the front and rear walls of the bag upon the tucked side walls, means to form squared shoulders on the bag, means to fold the end of the bag down upon one of said squared shoulders comprising a combined trimming and creasing device adapted to trim the edge of the bag at a certain distance above the enclosed contents and to form a crease in the bag parallel to and at 25 a uniform distance from the trimmed end, all of said means being relatively fixed, and means to adjust the bags toward and away from said means whereby to compensate for fluctuations in density of the enclosed material.
- 30 31. A machine for closing the mouths of filled bags comprising, means to tuck the side walls of the open end of the bag inwardly and to collapse the front and rear walls of the bag upon the tucked side walls, means to form squared shoulders on the bag, means to fold the end of the bag down upon one of said squared shoulders comprising a combined trimming and creasing device adapted to trim the edge of the bag at a certain distance above the enclosed contents and to form a crease in the bag parallel to and at a uniform distance from the trimmed end, all of said means being relatively fixed, and means to adjust the bags toward and away from said means whereby to compensate for fluctuations in density of the enclosed material.
- 35 32. A machine for closing the mouths of filled bags comprising; means to tuck the side walls of the open end of the bag inwardly and to collapse the front and rear walls of the bag upon the tucked side walls; means to form squared shoulders on the bag; means to fold the end of the bag down upon one of said squared shoul-
- ders comprising a combined trimming and creasing device adapted to trim the edge of the bag at a certain distance above the enclosed contents and to form a crease in the bag parallel to and at a uniform distance from the trimmed end, 5 folding bars adapted to fold the end of the bag once upon itself along said crease and means to fold the folded end of the bag down upon the said shoulder; all of said means being relatively fixed; and means to adjust the bags toward and away from said means whereby to compensate for fluctuations in density of the enclosed material.
- 10 33. The method of closing a filled bag comprising applying a uniform pressure to the top of the enclosed contents, trimming the mouth of the bag, and closing the mouth of the bag with reference to the top of the enclosed, compressed contents as a datum line.
- 15 34. A machine for closing the mouths of filled bags having the side walls of the open end of the bag tucked inwardly and the front and rear walls of the bag collapsed upon the tucked side walls comprising means to form squared shoulders on the bag, and means to fold the end of the bag down upon one of said squared shoulders, 20 and including a trimming device adapted to trim the edge of the bag at a certain distance above the enclosed contents.
- 25 35. A machine for closing the mouths of filled bags having the side walls of the open end of the bag tucked inwardly and the front and rear walls of the bag collapsed upon the tucked side walls comprising means to form squared shoulders on the bag, and means to fold the end of the bag down upon one of said squared shoulders, 25 and including a combined trimming and creasing device adapted to trim the edge of the bag at a certain distance above the enclosed contents and to form a crease in the bag parallel to and at a uniform distance from the trimmed end.
- 30 36. A machine for closing the mouths of filled bags having the side walls of the open end of the bag tucked inwardly and the front and rear walls of the bag collapsed upon the tucked side walls comprising means to form squared shoulders on the bag, means to fold the end of the bag down upon one of said squared shoulders comprising a combined trimming and creasing device adapted to trim the edge of the bag at a certain distance above the enclosed contents and to form a crease in the bag parallel to and at a uniform distance from the trimmed end, 35 and folding bars adapted to fold the end of the bag once upon said creased line.
- 35 37. A machine for closing the mouths of filled bags having the side walls of the open end of the bag tucked inwardly and the front and rear walls of the bag collapsed upon the tucked side walls comprising means to fold the end of the bag down upon one of said squared shoulders comprising a combined trimming and creasing device adapted to trim the edge of the bag at a certain distance above the enclosed contents and to form a crease in the bag parallel to and at a uniform distance from the trimmed end, 40 folding bars adapted to fold the end of the bag once upon itself along said creased line, and means to fold the folded end of the bag down upon the said shoulder.
- 40 38. A machine for closing the mouths of filled bags having the side walls of the open end of the bag tucked inwardly and the front and rear walls of the bag collapsed upon the tucked side walls comprising means to form squared shoulders on the bag, means to fold the end of the bag down upon one of said squared shoulders comprising a 45

- 50 55
- 55 60
- 60 65
- 65 70
- 70 75

combined trimming and creasing device adapted to trim the edge of the bag at a certain distance above the enclosed contents and to form a crease in the bag parallel to and at a uniform distance from the trimmed end, means to apply adhesive to said shoulder, folding bars adapted to fold the end of the bag once upon itself along said creased line, and means to fold the folded end of the bag down upon the said shoulder.

39. In a filled bag closing machine, means to trim the edge of the bag comprising a trimming device and means operable to grasp the end of the bag below the edge being trimmed and holding the same against pressure on the side of the bag, and means to apply adhesive to the side of the bag below the said grasping means while the end of the bag is so held.

40. In a filled bag closing machine, means to trim the edge of the bag comprising a trimming device and means operable to grasp the end of the bag below the edge being trimmed and holding the same against pressure on the side of the bag, and means to apply adhesive to the side of the bag below the said grasping means while the end of the bag is so held, said applying means comprising a fountain roll and a transfer roll reciprocated from said fountain roll to the bag.

41. In a filled bag closing machine, means to trim the edge of the bag comprising a trimming device and means operable to grasp the end of the bag below the edge being trimmed and holding the same against pressure on the side of the bag, and means to apply adhesive to the side of the bag below the said grasping means while the end of the bag is so held, said applying means comprising a fountain roll and a transfer roll reciprocated from said fountain roll to the bag, and means associated therewith to revolve said fountain roll during the reciprocation thereof.

42. In a filled bag closing machine of the type adapted to close the open end of a bag having its side walls tucked inwardly between the collapsed front and rear walls, means to fold the end of the bag upon itself, and means temporarily holding the folded end while folding the same upon the top of the enclosed contents, said means comprising a sliding plate movable across the top of the bag and adapted to press and smooth the folded end in the direction of the fold to draw the bag taut.

43. The method of closing a filled bag having its side walls tucked inwardly and its front and rear walls collapsed upon the side walls above the top of the enclosed contents comprising holding the collapsed end of the bag against movement and applying uniform pressure to the top of the enclosed contents, and folding the mouth of the bag upon itself with reference to the top of the enclosed compressed contents as a datum line for the line of folding.

44. The method of closing a filled bag having its side walls tucked inwardly and its front and rear walls collapsed upon the side walls above the top of the enclosed contents comprising holding the collapsed end of the bag against movement and yieldably applying uniform pressure to the top of the enclosed contents, and folding the mouth of the bag upon itself with reference to the top of the enclosed compressed contents as a datum line for the line of folding.

45. The method of closing a filled bag comprising

applying uniform downward pressure to substantially the entire upper surface of the enclosed contents of the bag to bring said surface into a plane and simultaneously drawing portions of the front and rear walls of the bag toward each other over said surface and into the plane thereof.

5

46. In a filled bag closing machine of the type adapted to close the open end of a bag, having its side walls tucked inwardly between the collapsed front and rear walls, means to fold the end of the bag upon itself and means engaging and folding the same upon the top of the enclosed contents, said last named means comprising a sliding plate movable across the top of the bag and adapted to yieldably press and smooth the folded end in the direction of the fold to draw the bag taut.

10

47. In a filled bag closing machine of the type adapted to close the open end of a bag having its side walls tucked inwardly between the collapsed front and rear walls, means to form a uniform closure comprising guides and feeding mechanism for intermittently advancing the filled bag in upright position between the guides, a combined trimming and creasing device operable during a dwell in the intermittent movement of the bag to trim the edge thereof and to form a crease at a definite distance from and parallel to the trimmed edge, and means to which the bag is then presented for folding the bag mouth along the crease and drawing the folded end down upon the top of the bag contents.

20

48. The method of closing filled bags comprising collapsing the mouth of the bag; applying downward pressure to level the upper surface of the enclosed contents; drawing portions of the front and rear walls toward each other into the plane of the top of the contents; applying adhesive to one of said portions; folding the bag mouth into said plane and drawing said bag mouth across said plane while pressing the same against said adhesive.

30

49. In a filled bag closing machine, means to tuck the side walls of the bag inwardly and to press the same against the top of the enclosed contents comprising tucking members and operating means to yieldably urge said tucking members into contact with said side walls.

40

50. A machine for closing filled bags comprising: means to fold the material of the bag above the level of the contents into the plane of such level, said means being operable at a pre-determined distance above such level, and means for trimming off sufficient bag material so that the folded edge of such material, when in the plane of such level, will lie within the cross section of the bag body.

50

51. In a filled bag closing machine of the type adapted to close the open end of a bag, having its side walls tucked inwardly between the collapsed front and rear walls, means to fold said open end upon itself, means to apply adhesive to the bag below said folded end and means engaging and folding said folded end upon the top of the enclosed contents and in engagement with said adhesive, said last named means including a member movable transversely across the top of the bag and adapted under yielding pressure to smooth the folded end in the direction of the fold to draw the bag taut.
